(57) **CLAIM**

The ornamental design for a bottle, as shown and described.

DESCRIPTION

FIG. 1 is a front elevation of a bottle showing my new design;

FIG. 2 is a rear elevation thereof;

FIG. 3 is a left side elevation thereof;

FIG. 4 is a right side elevation thereof;

FIG. 5 is a top plan view thereof;

FIG. 6 is a bottom plan view thereof;

FIG. 7 is a front elevation of a second embodiment of the bottle showing my new design;

FIG. 8 is a rear elevation of the second embodiment;

FIG. 9 is a left side elevation of the second embodiment;

FIG. 10 is a right side elevation of the second embodiment;

FIG. 11 is a top plan view of the second embodiment;

FIG. 12 is a bottom plan view of the second embodiment;

FIG. 13 is a front elevation of a third embodiment of the bottle showing my new design;

FIG. 14 is a rear elevation of the third embodiment;

FIG. 15 is a left side elevation of the third embodiment;

FIG. 16 is a right side elevation of the third embodiment;

FIG. 17 is a top plan view of the third embodiment; and, FIG. 18 is a bottom plan view of the third embodiment.

The broken line showing of the bottle cap in FIGS. 1-5, 7-11, and 13-17 is for illustrative purposes only and forms no part of the claimed designed.
